(57) **CLAIM**

The ornamental design for a stationary rowing machine, as shown and described.

DESCRIPTION

FIG. 1 is a perspective view of a first embodiment of a stationary rowing machine showing my new design.

FIG. 2 is a side view thereof.

FIG. 3 is an opposite side view thereof.

FIG. 4 is a front view thereof.

FIG. 5 is a rear view thereof.

FIG. 6 is a top view thereof.

FIG. 7 is a bottom view thereof.

FIG. 8 is a perspective view of a second embodiment of a stationary rowing machine showing my new design.

FIG. 9 is a side view thereof.

FIG. 10 is an opposite side view thereof.

FIG. 11 is a front view thereof.

FIG. 12 is a rear view thereof.

FIG. 13 is a top view thereof; and,

FIG. 14 is a bottom view thereof.

The broken lines in the drawings illustrate portions of the stationary rowing machine that are not part of the claimed design.

1 Claim, 14 Drawing Sheets
